UNITED STATES PATENT OFFICE

GEORGE C. ERB, OF ROSELLE PARK, NEW JERSEY, ASSIGNOR TO AMERICAN CAN COMPANY, OF NEW YORK, N. Y., A CORPORATION OF NEW JERSEY

COMPOUND LINING MACHINE

Application filed August 15, 1927. Serial No. 212,885.

This invention relates in general to machines for applying a lining compound or gasket material to the flanges of flanged can ends to enable them to be interfolded with the flanges of flanged can bodies to form the now usual hermetic solderless end seams of the tin can of commerce. The invention has more particular reference to the application of compound to the end by a printing die and 10 through the employment of a compound of relatively thick or viscous character.

In the die lining of can ends from certain standpoints it is desirable that the die move up from beneath the surface of a body of 15 compound in a tank and imprint upon the flange of the end the desired amount of compound upon the can end. The ends, to receive a compound from a die thus moving, must be arranged of course with the flange area to be 20 lined facing downwardly, and while the material is of sufficient viscous character to cause it to adhere in desired amount to the end, it is desirable that the end be immediately thereafter inverted and final drying accomplished 25 in the inverted position to the end that the material may spread to form the film required over the area provided for its reception.

An important object of the invention is in the provision of means for applying a lining compound to the flanges of can ends in downwardly opening position, and in inverting and delivering the lined can ends with the flanges opening upwardly for drying the compound and further operations upon the 35 can ends in upright position.

A further object of the invention is the provision of means for receiving can ends in one position and for delivering them at a different elevation in an inverted position.

40 A further important object of the invention is in the provision of improved means for preventing the application of lining compound when there is no can end in the compound receiving position.

45 A further important object of the invention is in the provision of a horizontal carrier with a number of faces provided with magnetic means for holding a can end in position on each of the faces.

50 A still further object of the invention is

in the provision of a compound receptacle which is easily removed in its entirety without the removal of any other screws or parts, and without affecting the compound die applying mechanism which moves within the receptacle. 55

A still further important object of the invention is in the provision of improved clutch mechanism for manually controlling the operation of the machine. 60

Numerous other objects and advantages of the invention will be apparent as it is better understood from the following description, which, taken in connection with the accompanying drawings, discloses a preferred embodiment thereof. 65

In the drawings:

Figure 1 is a side elevation of an improved compound lining machine embodying the features of this invention with a discharge conveyor therefor shown in section; 70

Fig. 2 is a plan view of the machine shown in Fig. 1;

Fig. 3 is a cross-section illustrating the driving mechanism, as taken substantially 75 on a line 3-3 of Fig. 2;

Fig. 4 is a section taken substantially on the line 4-4 of Fig. 3, showing the carrier drum, the compound applying die and the driving mechanism; 80

Fig. 5 is a plan view, partly in section, showing the cover feeding mechanism, the compound lining mechanism, and the no-end-no-compound feed device; 85

Fig. 6 is a sectional elevation taken substantially on the line 6-6 of Fig. 5;

Fig. 7 is an elevation, with parts shown in section, of the handle controlling clutch mechanism, taken substantially on the line 7-7 of Fig. 3; 90

Fig. 8 is a front elevation of the lining die mechanism and the mounting for the compound lining receptacle, the latter being omitted for clearness;

Fig. 9 is a detail side elevation of the latch 95 for locking the compound lining receptacle in place; and

Fig. 10 is a sectional view taken substantially along the line 10-10 in Fig. 5.

Referring more particularly to the draw- 100

ings, a machine support frame designated generally with the numeral 11 is mounted in a suitable supporting base 12, and carries the operating parts of the machine. A discharge runway 13 is located adjacent the upper part of the machine in which moves a conveyor chain 14 for carrying discharged can ends 15.

The can ends 15 are stacked in a magazine comprising a base plate 16 supported by the frame 11 and rods 17 extending upwardly therefrom so the can ends can be fed at the top.

The lowermost can end in the magazine is separated from the remaining can ends and moved horizontally by a reciprocating feed bar 18, as shown more clearly in Figures 5 and 6, which has a lower projection 19 to engage below the edge of a can end 15 and an edged plate 20 with a rounded extremity 21 spaced above the extension 19 and adapted to engage the edge of the lowermost can end in the magazine.

The feed bar 18 is attached to a plate 22 slidable in guides 23 supported by the machine frame 11. The plate 22 is attached to a block 24 pivoted to one end of an adjustable link 25, the other end of which is pivoted to the upper end of an operating lever 26 (see Fig. 1), the lower end of which is pivoted in a bracket 27. This lever is oscillated by a link 28 pivoted at one end of the lever, and at the other to a crank disc 29 at the end of an operating shaft 30.

A cut-out lever 31 (Fig. 5) is operated by the reciprocation of feed bar 18, which is formed on one side with a cam surface 32. The lever 31 is pivoted intermediate its ends and carries a cam engaging roller 33 at one end, which is held against the cam surface 32 by a spring 34 attached at one end to a projection 35 of the lever 31, and at the other end to the machine frame 11 by a screw 36. At the other end of the lever it carries a separator blade 37 adapted to pass between the lowermost can end in the magazine and the next one to it in timed relation, so that when the feed bar 18 is moved to discharge the lowermost can end from the magazine, the roller 33 will ride up on the cam surface 32, moving the separator blade 37 inwardly to partially support the stack of can ends until the feed bar 18 is moved oppositely into position to again engage the lowermost can end.

The can end carrier to which the can ends are fed comprises a rotatable drum 40 mounted for rotation on a horizontal shaft 41, as shown more clearly in Fig. 4, by means of a key 42 wedged in position by a bolt 43, movable in a recess 44 in the end of the shaft and secured in place by a nut 45 at the outer end of the bolt.

Each supporting face of the carrier drum 40 (Figs. 4 and 6) comprises a plate 46 and an attached disc 47, both secured to a pro-

jecting core piece 48 forming an annular face 49 corresponding to and for receiving the shape of a can end to be lined. In the drawings a circular face is shown, although a can end of any desired shape may be accommodated. Surrounding each core piece 48 below the face plates is a magnetic winding coil 50 for energizing the magnets thus formed and for attracting and holding can ends in position on the carrier.

Current is supplied to the magnet coils 50 by collector rings 51 and 52 (see Fig. 4) connected by conductors 53 and 54 respectively with the windings, the rings being engaged at another location by brushes (see Fig. 8) 55 and 56, which are in turn connected to electrical supply conductors 57 and 58.

The carrier drum shown is formed with six can end receiving faces, each of which is brought successively in position to receive a can end from the feeding bar 18, the can end being supported in its feeding movement by plates 59, which constitute an extension of the magazine or the machine frame 11. At the time of the feeding movement, the carrier drum is held stationary and the movement of a can end below one of the core pieces 48 causes the can end to be held by the magnetism of the drum in the lining position.

For applying the compound lining to a can end in the lining position, a die 60 is mounted at the end of an arm 61 by means of a bolt 62 which suspends the die in a receptacle 63 of lining compound 64. The outer end 61' of the arm 61 is secured by screws 62' to a slide 65 movable in vertical guides 66 formed in a frame part 67 projecting upwardly from the main frame 11. At the lower end of the slide 65 it is connected by a coupling 68 (see Figs. 4 and 8) with the upper threaded end of a shaft 69 held at one end of a sleeve 70 by a shoulder 71 on the shaft and a spring 72 within the sleeve bearing against the shoulder 71 and against a bushing 73 threaded in the lower end of the sleeve through which the shaft 69 also extends, said shaft having a squared portion 74 at its outer end and a nut 75 to engage the coupling 68 for adjustment.

To raise and lower the lining device, the sleeve 70 is provided with a crank pin 76 mounted in a crank disc 77 at the end of a shaft 78 journalled in bearings 79 of the frame extension 67 and 80 of a gear housing 81. The continuous rotation of shaft 78 reciprocates the die 60, immersing it in the compound 64 and raising it therefrom to apply the compound to a can end in the lining position. The yielding connection between the sleeve 70 and the shaft 69 is to stop the die without interfering with the rotation of shaft 78 when a can end is not in the lining position.

To control the operation of the lining die a stop bar 82 is mounted for transverse movement in the frame extension 67 (see Figs. 4,

5 and 8) in the path of movement of a block 83 secured to the back of the slide 65, the rod and the block having corresponding recesses 84 and projections 85 respectively so located 5 that when the rod is in one position the projections 85 will enter the recesses 84 permitting a full raising movement of the die 60, but when the rod 82 is in another position the projections 85 will not engage in the recesses 10 84 of the rod and the full lining applying movement of the die will be arrested, bringing into action the flexible connection between the shaft 69 and sleeve 70. The oscillation of the rod 82 is effected by the mechanism shown 15 more clearly in Fig. 5, which comprises an arm 91 clamped by a screw 91' to a lever 96' formed with a stud 92', pivoted to the machine frame 11 adjacent the can end magazine, the stud 92' being secured to a lever 86 20 connected by means of a rod 87 with another lever 88 pivoted at 88' to the frame 11. Lever 88 carries an adjustable contact stud 89 in the path of a contact block 90 attached to the feed bar 18, so that in the rearward movement 25 of the feed bar the contact stud 89 is engaged, rocking levers 88 and 86 correspondingly. The arm 91 has a fastening device 92 operating in a slot 93 for adjustably securing it to the lever 96'. The outer end of the arm 91 is 30 formed with a slot 94 for engaging a pin 95 carried by the stop bar 82, and one end of the lever 96' is formed with an inclined contact face 96 normally disposed in the path of a can end moved by the feed bar 18. With this 35 construction, it is obvious that the forward feeding movement of the feed bar 18 moves a can end 15 in engagement with the contact surface 96 of the lever 91, causing a corresponding movement of the stop bar 82 to 40 position the recesses 84 thereof in a position to receive the projection 85 of the contact block 83 of the die operating slide 65, and upon the rearward movement of the feed bar 18 the contact stud 89 is engaged by the block 45 90 rocking the levers 88, 86, 96' and 91 in the reverse direction and moving the stop bar 82 to the stop position. If no can end is moved by the feed bar 18 in its next forward movement, the lever 96' will not be engaged, and 50 the stop bar 82 will not be moved from its stop position, which insures that a can end must be in proper position at the lining station before the lining die is fully actuated to apply a lining.

55 In the mounting the compound receptacle 63 so it can be removed from its operating position, as shown in Fig. 4, without disturbing any of the die operating mechanism, a vertical pivoting rod 97 (see also Figs. 5 and 8) is mounted at its ends in bearing brackets 98 and formed as a part of one of the guides 66 secured to the upright frame part 67. The receptacle is provided with a corner extension 99 having a vertical bore 100 to snugly fit 65 the rod 97 with a slot 101 in the outer edge of

the bore, as shown more clearly in Fig. 5, less in width than the diameter of the bore 100. The lower portion of the rod 97 is formed with two diametrically opposite flattened portions 102 of a length and diameter to receive 79 the slot 101 of the receptacle 63 when it is in lowered position on the rod, and when it is rotated to register the slot 101 with the flattened portion 102, the receptacle 63 may be bodily removed from or attached to the rod 75 97.

In attaching the receptacle to the pivoting rod, the slot 101 is passed over the flattened portion 102 and the receptacle is raised above the flattened portion 102, so that the bore 80 100 is rotatably engaged by the circular bore portion of the rod 97, and the receptacle 63 is rotated to engage a lug 103 on its opposite lower corner with a projection 104 on the opposite guide 66. To hold the receptacle 85 in this position, a latch 105 (see Figs. 5, 6, 8 and 9) is pivoted in a bracket 106 on the frame 67 and has an enlarged head 107 adapted to engage in a slot 108 of a lug 109 projecting from the side of the receptacle 63. The latch 89 is simply raised to disengage it from the lug 109, the enlarged head holding the lug against outward movement when the latch is in engaging position. With this construction the receptacle 63 can be applied or removed without affecting the operating mechanism for the lining die 60. A substantial mounting is afforded to support an extension 110 of the receptacle 63 in which a bottle 111 for replenishing the receptacle is held in 100 inverted position (see also Figs. 1 and 2) which operates upon the water bottle principle to maintain a certain level of the lining compound 64 in the receptacle 63.

After a can end has been supplied with lining compound by the die 60, it is rotated by the carrier drum 40 in a step by step movement until the can end is inverted and brought to a position at the top of the drum. From this position the can end is disengaged upon 105 a further movement of the drum by means of a blade 112, which extends into slots 113 formed in the adjacent angular edge between two can end supporting faces, so that the blade engages below a can end as the drum is rotated, lifting the can end from engagement with the face of the drum to which it is held by the magnetic core piece. At the far side of each face of the drum, are blocks 114 which in their uppermost positions engage the adjacent edge of a can end as it is raised by the stripper blade 112, and as the drum continues to rotate in its step by step movement, the blocks 114 push the can end along the blade and deposits it in the conveyor 13 (see Figs. 110 115 and 2) under a baffle plate 115 where it is engaged by the conveyor chain 14.

A step by step movement is given to the carrier drum by a Geneva mechanism illustrated more clearly in Figs. 3 and 4. A Geneva 115 120 125 130

wheel 116 is secured to the shaft 41, which carries the magnetic drum 40 by fastening screws 117 and has radial slots 118 corresponding in number to the poles and can end 5 engaging faces of the carrier drum 40. A roller 119 projecting from the face of a disc 120 rotatable upon a stud 121 supported by the gear housing 81 forms a pinion for engaging in the slots 118 of the Geneva gear. 10 This disc 120 is rotated by a spur gear 122 secured thereto and meshing with a corresponding gear 123 secured to the shaft 78, so that the continuous rotation of shaft 78 causes a continuous rotary movement of the roller 15 119 about the shaft 121, the roller engaging successive slots 118 for moving the Geneva wheel 116 in a well-known step by step manner.

In order to lock the Geneva wheel 116 and 20 consequently the carrier drum 40 in any one of its several positions for receiving can ends and holding them at the lining station, the Geneva wheel is provided intermediate the radial slots 118 with locking notches 124 25 adapted to be engaged by a spring pressed block 125 movable in a housing 126 attached to the inside of gear housing 81 and pressed in engaging position by a spring 127. To move the block into and out of engagement 30 a lever 128 is mounted at one end upon a pivoting stud 129 attached to the gear housing 81 and has an extremity 130 extending through a slot 131 in the side of the housing 126 into engagement with a notch 132 in the 35 side of the block 125. This lever is operated by a contact roller 133 adapted to engage the cam face 134 of the disc 120 which carries the roller 119 for operating the Geneva wheel, the spring 127 pressing the lever 128 and its 40 roller 133 toward the cam surface 134, which thereupon operates the lever and the locking block 125 in timed relation to properly engage the Geneva wheel.

A driving connection is made with the gear 45 123 secured to the shaft 78 and operating parts of the machine by engagement with a driving gear 135 mounted on the shaft 30, as shown in Figs. 3 and 7. The driving gear 135 extends from a sleeve portion 136 mounted upon and secured by a key 137 to the driving shaft 30. The gear 135 also extends parallel to a flange 138 extending from a sleeves 139 loosely mounted on the shaft 30 and having a driving gear or sprocket 140 55 secured thereto for the driving engagement of a chain 141, as shown in Fig. 2. The flange 138 is formed with a hole 143 adapted to engage a locking pin 144 carried by the gear 135 and moved therefrom into engagement 60 with the hole in the flange for driving the gear 135 with the power operated sleeve 139.

To operate the pin 144, there is a collar 65 145 slidable on sleeve 136 and having a projection 146 which is secured to and supports the pin 144 in a hole 147 of the gear 135

which registers with the hole 143 in the flange 138. A spring 148 is interposed between the collar 145 and the sleeve 136 tending to press the pin 144 into engagement with the hole 143. 70

To control the operation of the engaging pin 144 a hand lever 150 is fixed to a rock shaft 151 and carries an extending lug 152 (see also Fig. 1) in which is a lock pin 153 pressed by means of a spring 154 into engagement with a pocket 155 or a pocket 156 in the outer face of the frame 23 adjacent thereto. The lock pin 153 has a cross pin 157 to provide a hand hold for withdrawing the pin from its engagement with either one 80 of the pockets 155 or 156, and for rotating the hand lever 150 and the shaft 151 accordingly. At the opposite end of the shaft 151 is a block 158 carrying a boss 159 which forms a housing for a fixed pin 160 and a 85 sliding pin 161 pressed normally outward by spring 162 but limited in its outward movement by a shoulder 163.

To control the operation of the collar 145, two flanges 164 and 165 are formed on the 90 outside of the collar providing a channel for engaging the spring pressed pin 163, the inner flange having a cam portion 166 for engaging the fixed pin 160 when it is moved toward the collar 145. 95

In the operating position of the hand lever 150 the shaft 151 is rotated to withdraw both of the locking pins 160 and 161 from engagement with the collar 145 so that it will move the pin 144 in position to lock the gear 100 135 and the flange 138 for rotation together. When the hand lever 150 and the shaft is rotated into the other position, the pin 160 will engage the cam surface 166 of the collar 145, moving the collar along the sleeve 136 105 against the pressure of spring 148. Before the pin engages the cam surface 166 the spring pressed pin 163 will engage the outer surface of the flange 164 and will not move downwardly into the groove between the 110 flanges 164 and 165 until the collar has been moved laterally to register the pin 163 with the groove. The pin 163 will then hold the collar 145 and the pin 144 out of engaging position until the hand lever 150 is again 115 operated.

The hand lever 150 thus controls the operation of the entire machine, which is entirely automatic, requiring only the filling of the magazine with can ends and a supply of lining compound. The can ends are fed automatically with the flanges turned down and delivered with the lining applied at a different elevation and in inverted position, so that the flanges are turned up and the can 125 ends discharged into a transverse conveyor. The operation of the mechanism is intermittent, the can end carrier drum moving toward, not away from, the can end magazine in inverting the lined can ends. 130

It is thought that this invention and many of its attendant advantages will be understood from the foregoing description, and it will be apparent that many changes may be made in the form, construction and arrangement of the parts without departing from the spirit and scope of the invention or sacrificing all of its material advantages, the form hereinbefore described being merely a preferred embodiment thereof.

10 I claim:

1. In a compound lining machine, means for applying a lining compound upwardly to a can end, and means for delivering a can 15 end lined thereby in an inverted position whereby the compound is retained within the end.

2. In a compound lining machine, means for applying a lining compound to the under side of a can end, and mechanism for inverting a lined can end in delivering it from the compound lining means whereby the compound is retained within the end.

3. In a compound lining machine, means 25 for applying a lining compound to one face of a can end, feeding means for applying can ends one at a time to the lining means, and means for inverting the can ends in discharging them from the lining means whereby the compound is retained within the end.

4. In a compound lining machine, means for feeding can ends one at a time from a magazine stack, lining mechanism for applying a compound to the under side of each 35 can end as it fed from a stack, and means for inverting the can ends after the lining operation whereby the compound is retained within the end.

5. In a compound lining machine, means 40 for feeding can ends in succession, in horizontal position, a rotatable carrier for receiving the can ends, means for applying a lining compound to the under surface of can ends on the carrier, and means for disengaging lined can ends from the carrier in inverted position whereby the compound is retained within the end.

6. In a compound lining machine, means for feeding can ends in succession, a rotatable 50 magnetic carrier for receiving can ends on the faces thereof, means for applying a lining compound to the lower face of a can end supported by said carrier, the rotation of the carrier inverting the can ends, whereby the compound is retained within the end, and means for disengaging the can ends from the magnetic carrier in discharging them therefrom.

7. In a compound lining machine, a rotatable magnetic carrier for can ends, means 60 for feeding can ends in succession to the under side of the carrier, means for applying a lining compound to the under side of can ends supported by the carrier, means for rotating the carrier to invert the lined can

ends, whereby the compound is retained within the end, a conveyor adjacent the upper edge of the carrier, and means to engage the under side of a can end in its upper inverted position in discharging it from the carrier to said conveyor.

8. In a compound lining machine, a horizontally rotatable magnetic carrier, means for feeding can ends in succession to the under side of the carrier, lining means movable upwardly to apply a lining compound to the under surface of the can end on the carrier, means for rotating the carrier to invert the can end, a conveyor adjacent the upper surface of the carrier extending at an angle to the can end feeding means, and discharging means engageable with the under side of a can end in its inverted position for disengaging a can end from the carrier as it rotates and discharging it upon said conveyor whereby the compound is retained within the end.

9. In a compound lining machine, means for feeding can ends one at a time to a lining position, a lining die movable vertically to apply a lining compound to the under side of a can end in the lining position, a compound receptacle in which the lining die is immersed, and means for supporting the receptacle for pivoted and downward sliding movement to remove the receptacle without affecting the lining die mechanism.

10. In a compound lining machine, means for holding can ends at a lining station, a lining die vertically movable to apply a lining compound to the can ends, and a compound receptacle for the lining die comprising a pivoting rod and a latch for holding the receptacle in raised position to immerse the lining die, the rod having a flattened portion and the receptacle having a corresponding slot for disengaging the receptacle from the rod, by releasing the latch and lowering the receptacle to register the slot with the flattened portion of the rod without affecting the lining die mechanism.

11. In a compound lining machine, means for receiving and holding a can end exposed at its under side, a lining die and means for moving it to apply a lining to the under side of a can end, a bar having projections disposed in the path of the die moving means, means depending upon the presence of a can end in the receiving position to move the bar out of engaging position, and a flexible connection in the die moving means allowing engagement of the die moving means with the bar when a can end is not in the lining position.

12. In a compound lining machine, a can end feed comprising a reciprocable bar for engaging and moving can ends, means engaged by a can end and said bar comprising an oscillatable lever, a stop bar having projections thereon and moved by said lever, a

die for applying compound to can ends delivered by the feeding bar to the lining position, and a yielding mechanism for operating the die having projections for engaging the 5 projections of said stop bar when the latter is in one position to prevent the movement of the lining die to a can end engaging position.

13. In a compound lining machine, a carrier for receiving and holding can ends in succession at a lining station, means for applying a lining to can ends at said station, a stack feeder for engaging the lowermost can end in a magazine and delivering it to 5 said carrier, said means comprising a reciprocable bar having a notched end for engaging a single can end and a cam surface on one side thereof, and a pivoted cut-out lever having a cam roller at one end engaging the cam 10 surface of the bar, and a blade at the other end moved by the bar into position to engage and partially support the stack of can ends above the lowermost can end which is being fed by said bar.

14. In a compound lining machine, a rotary magnetic can end carrier having a plurality of faces, means for feeding can ends to the faces in position below the carrier, means for rotating the carrier intermittently 10 to bring succeeding faces in the lowermost position, a locking device for holding the carrier in position, and means for applying a lining compound to can ends in the lining position at the under side of the carrier.

15. In a compound lining machine, a rotatable magnetic carrier, means for delivering can ends to the under side of the carrier and discharging them in inverted position from the upper side of the carrier, a lining die 10 movable to engage can ends in the lining position at the under side of the carrier, means for intermittently moving the carrier to bring successive faces thereof into the lining position, a lock for holding the carrier in 15 different positions at the lining station, a continuous drive for the intermittent moving means, comprising a driving member with a perforation therein, a gear carrying a pin movable into said perforation, a spring 10 pressed collar tending to hold the pin in engagement with the perforation of said driving member, and means for controlling the movement of the collar, comprising a rotatable shaft and a hand lever mounted 15 thereon for movement into either one of two positions, a head carried by the shaft with two contact pins engageable with the collar in the different positions of the shaft, the collar having an inclined portion and one of 20 the pins engaging the inclined portion to move the collar, and a pin carried thereby out of the perforation of the said driving member.

16. In a compound lining machine, a rotatable magnetic carrier with a plurality of

can end engaging faces, means for delivering can ends in succession to the separate faces, a compound applying die movable from below to apply lining compound to a can end upon the lowermost face of the carrier, means for rotating the carrier, step by step, to invert a can end carried thereby, a conveyor arranged adjacent the uppermost face of the carrier, the carrier having a slot extending below each face of each carrier, a fixed finger adapted to 70 extend in the slot below each can end in the uppermost position of the carrier, and an engaging block at the end of each face opposite the finger for discharging the uppermost can end by the engagement of the finger from the carrier as it rotates upon said conveyor. 80

17. In a compound lining machine, a rotatable magnetic carrier having a plurality of separate can end engaging faces with slots in the faces and feeding blocks at the rear 85 side of each face, means for feeding can ends to the faces for applying lining thereto, and means comprising a finger extending into the slots of the carrier below a lined can end for disengaging a can end from the carrier as it 90 rotates, said block engaging the rear face of a can end disengaged by the finger for pushing it from the carrier in discharging the can end.

18. In a compound lining machine, a rotatable magnetic carrier having a plurality of can end receiving faces, means for feeding the lowermost can end from a stack to the successive faces of the carrier, a cut-out device operated by said feeding means to properly support the stack of can ends above the lowermost one during the feeding operation, a vertically movable die for applying lining compound to the under face of a can end supported by the carrier, oscillating means actuated by a can end and said feeding means, and including a stop bar positioned thereby to control the movement of the die depending upon the presence of a can end at the lining station, means for intermittently moving the die and the carrier, a locking device for positioning the carrier in any one of several positions corresponding to its faces, a conveyor for receiving lined can ends at a different elevation and inverted from the position at which the lining is applied, and means for disengaging the can ends and discharging them upon said conveyor by the rotation of the carrier. 105 110 115 120
